UNITED STATES PATENT OFFICE.

LEWIS W. McCANDLESS, OF CHICAGO, ILLINOIS.

PENCIL LEAD.

1,405,791.

Specification of Letters Patent. Patented Feb. 7, 1922.

Application filed April 12, 1920. Serial No. 373,078.

To all whom it may concern:

Be it known that I, LEWIS W. McCANDLESS, a citizen of the United States, residing at Chicago, in the county of Cook and State 5 of Illinois, have invented certain new and useful Improvements in Pencil Leads, of which the following is a specification.

My invention relates to lead pencils, and particularly to a pencil lead which is formed 10 with one or more grooves in its surface so that there is always presented a sharp corner or edge for writing purposes.

My invention pertains to leads for pencils which may be used as renewable leads for 15 holders or permanently secured in a lead pencil of the commercial variety.

An object of my invention is to provide a lead for pencils which will not have to be sharpened but which will always present a 20 substantially sharp point for writing purposes as it wears away in usage. 70

Another object is to provide a pencil lead having means for always presenting a sharp point for writing, which is accomplished by 25 forming one or more grooves in the surface of the lead, thereby providing "corners" or "points" at the end of the lead as the same is worn in use.

A further object is to provide a lead for 30 pencils which may be made with the minimum of expense and which will always provide a sharp point for writing purposes.

These and other objects of my invention may be observed from the drawings, in 35 which—

Figure 1 is a view of a metallic pencil exaggerated in size in which is inserted a lead embodying my invention;

Figure 2 is an enlarged elevational view of 40 a portion of the lead made in accordance with the preferred form of my invention; and

Figure 3 is a vertical section on line 3—3 of Figure 2.

I accomplish the objects of my invention 45 by forming one or more grooves, preferably in spiral form, in the surface of a pencil lead, so that as the lead is worn in use there is always presented at least one sharp corner 50 for a point. By providing a plurality of

grooves crossing one another many such diamond-shaped projections are formed, presenting successive sharp corners at the end of the lead which serve as points. In the drawings a lead 5 is shown as being provided with a series of spiral grooves 6 and 7 arranged to cross one another forming a plurality of diamond-shaped portions which have the corners 8, 9, 10 and 11 thereon. It will be observed that as the lead is 55 used in service at least one sharp corner is presented to serve as a point. By referring to Figure 3 it will be noted that six corners are presented as points, so that as one of these is worn the pencil may be turned to 60 employ another corner as a point. This feature is important in view of the present popularity of refillable pencils, and as a means for providing a lead for refillable pencils in which there is always presented a point for 65 use without sharpening. 70

My lead is adaptable for use in all kinds of pencils, refillable, magazine and wooden or paper covered ones.

While I have described more or less precisely the details of construction of my invention, I do not wish to be understood as limiting myself thereto, as I contemplate changes in form and the proportion of parts and substitution of equivalents as circumstances may suggest or render expedient, without departing from the spirit of my invention. 75

I claim:

1. In a device of the class described, a lead 80 for pencils provided with a plurality of longitudinally extending grooves formed in the surface thereof, the grooves arranged to intersect to provide a plurality of successive points in the length of said lead. 90

2. A pencil lead having a plurality of intersecting spiral grooves formed in the surface thereof, thereby providing a plurality of substantially diamond-shaped projections which successively present sharp edges and corners at the end of the lead for serving as points for writing purposes. 95

Signed at Chicago, Illinois, this 5th day of April, 1920.

LEWIS W. McCANDLESS.
